Phil. T. Dodge

UNITED STATES PATENT OFFICE.

HIATT WILBUR, OF ALMONT, MICHIGAN.

TWO-WHEELED VEHICLE.

SPECIFICATION forming part of Letters Patent No. 358,908, dated March 8, 1887.

Application filed July 30, 1886. Serial No. 209,553. (No model.)

To all whom it may concern:

Be it known that I, HIATT WILBUR, of Almont, in the county of Lapeer and State of Michigan, have invented certain Improvements in Road-Carts and Other Two-Wheeled Vehicles, of which the following is a specification.

The aim of my invention is to provide a running-gear by which the body may be securely supported but permitted to rise and fall with an easy action when traveling over uneven ground, and to avoid the vibratory motion which is commonly imparted to the body by the movement of the horse.

15 The accompanying drawing represents the frame or running-gear of the cart constructed on my plan, the box or body, to which my invention has no special relation, being omitted in order to expose other parts to view.

20 Referring to the drawing, A A represent the two main wheels, of ordinary construction, mounted on opposite ends of the metal axle B, which latter is curved upward at the middle, as shown at a.

25 C represents the thill, formed with or secured rigidly to horizontal arms or side bars, D, which are extended rearward and clamped or otherwise secured firmly to the ends of the axle, as shown at b.

30 E represents a horizontal frame of substantially a Y form suspended at its center by a link, c, or equivalent connection from the arched portion of the axle. At its forward end this frame is attached to a cross-bar, F, forming in effect a part thereof, the ends of which are provided with stirrups d, riding in slotted plates, stirrups, or equivalent horizontal guides e on the arms D. The purpose of this bar is to maintain the frame E in a horizontal position 40 and to prevent it from tipping or overturning.

G G represent two arched or semi-elliptic springs located one at each side of the frame and extending longitudinally thereof, their forward ends being connected by links or otherwise to the extremities of the cross-bar and their rear ends connected by links f, or equivalent connections, to the rear arms of the frame E. Upon these springs, midway of their length, I propose to mount the box or 45 body of the vehicle in any appropriate man-

ner. I prefer to secure in each spring a longitudinal bar or bolster, H, and to connect the sides of the body to the ends of these bolsters by metal arms, such as are commonly employed in similar places. As these connections form no part of the present invention, and as the body may be connected to the springs in any suitable manner, it is deemed unnecessary to illustrate these details herein.

It will be observed that under my construction the entire weight of the body will be received upon the springs G, transmitted thence to the frame E, and finally supported from the axle entirely, or practically so, by the link c. The slotted connection at the front permits 65 the body, springs, and frame E to play freely forward and backward, thus relieving them from the vibrations which they would otherwise receive.

While I prefer to construct the frame E in 70 the form represented, it is to be understood that it may be modified in form at will, provided only it is adapted for suspension at the center by the links c and to sustain at its corners the ends of the longitudinal springs.

In some instances I have divided or forked the forward end of the frame E, turning its ends outward to enter the guides e, as indicated in dotted lines, thus dispensing with the cross-bar F.

Having thus described my invention, what I claim is—

1. In a two-wheeled vehicle, the combination of the supporting-wheels, the axle, the thills having rigid connections to the axle, the frame E and the links by which it is suspended centrally from the axle, the horizontal sliding connection between the front end of said frame and the thills, and the longitudinal springs connected to the frame E, substantially as described.

2. In a two-wheeled vehicle, an axle having an upward curvature at the middle, in combination with a spring-supporting frame suspended from the arched portion of the axle 95 by a link, substantially as described, whereby the frame may be supported in a horizontal plane coinciding substantially with the ends of the axle.

3. In a two-wheeled vehicle, the combina- 100

tion of an axle, a frame, E, suspended midway of its width from the axle, and two longitudinal springs passing above the ends of the axle and connected at their extremities to the 5 underlying frames.

4. In a two-wheeled vehicle, the combination, with an axle and thills attached thereto, of a spring-supporting frame connected at its forward corners to the thills or thill-arms and 10 at its center to the axle.

In testimony whereof I hereunto set my hand, this 5th day of July, 1886, in the presence of two attesting witnesses.

HIATT WILBUR.
